US00D705268S

(12) **United States Design Patent**
Pindell

(10) **Patent No.:** **US D705,268 S**
(45) **Date of Patent:** **** May 20, 2014**

(54) **EXSICCATE DEVICE**

- (71) Applicant: **Pindell Engineering Inc.**, Port Townsend, WA (US)
- (72) Inventor: **Richard Pindell**, Port Townsend, WA (US)
- (73) Assignee: **H2Out, Inc.**, Sequim, WA (US)
- (**) Term: **14 Years**
- (21) Appl. No.: **29/446,013**
- (22) Filed: **Feb. 19, 2013**

Related U.S. Application Data

- (63) Continuation of application No. 12/841,431, filed on Jul. 22, 2010, now abandoned.
- (51) **LOC (10) Cl.** **15-01**
- (52) **U.S. Cl.**
USPC **D15/5**
- (58) **Field of Classification Search**
USPC D15/1-5; 422/179, 177, 211, 213; 136/253; 60/302, 299; D12/400, 194; D23/365; 34/482; 55/275, 387, 316, 55/482

(57) **CLAIM**

The ornamental design for an exsiccate device, as shown and described.

DESCRIPTION

FIG. 1 is a side perspective view of the exsiccate device showing my new design in an environment in accordance with the embodiment;

FIG. 2 is a side perspective view in another environment thereof;

FIG. 3 is a front perspective view thereof;

FIG. 4 is a front elevational view thereof;

FIG. 5 is a rear elevational view thereof;

FIG. 6 is a side elevational view thereof;

FIG. 7 is a side elevational view thereof;

FIG. 8 is a top plan view thereof;

FIG. 9 is a bottom plan view thereof; and,

FIG. 10 is an exploded, front perspective view thereof.

The broken lines depict environmental structure as well as portions of the exsiccate device that form no part of the claimed design.

1 Claim, 10 Drawing Sheets
